(57) **CLAIM**

The ornamental design for a robot, as shown and described.

DESCRIPTION

FIG. 1 is a front elevation view of the robot showing our new design;

FIG. 2 is a top plan view thereof;

FIG. 3 is a bottom plan view thereof;

FIG. 4 is a left side elevated view thereof;

FIG. 5 is a rear elevation view thereof;

FIG. 6 is perspective view thereof;

FIG. 7 is a left side elevated view thereof showing the screen of the robot turned to the left;

FIG. 8 is a right side elevated view thereof showing the screen of the robot turned to the right;

FIG. 9 is a left side elevated view thereof showing the screen of the robot tilted upwards; and,

FIG. 10 is a left side elevated view thereof showing the screen of the robot tilted downwards.

The broken lines in the drawings depict unclaimed environmental subject matter.

1 Claim, 9 Drawing Sheets
